(57) CLAIM

The ornamental design for an automobile tire as shown and described.

DESCRIPTION

FIG. 1 is a perspective view of an automobile tire showing our design;

FIG. 2 is a front view thereof;

FIG. 3 is an enlarged perspective view of a portion defined by lines 3-3 in FIG. 1;

FIG. 4 is an enlarged front view of a portion defined by lines 4-4 in FIG. 2; and,

FIG. 5 is an enlarged front view of a portion defined by lines 4-4 in FIG. 2 with all of the environmental subject matter being removed for clarity purposes.

In the drawings, the darkened out portions depict environmental subject matter only and form no part of the claimed design.
